UNITED STATES PATENT OFFICE.

HENRY E. PROCUNIER, OF CHICAGO, ILLINOIS.

LAMP HOLDER AND ADJUSTER.

1,254,068.

Specification of Letters Patent. Patented Jan. 22, 1918.

Application filed January 25, 1917. Serial No. 144,394.

To all whom it may concern:

Be it known that I, HENRY E. PROCUNIER, a citizen of the United States, residing at Chicago, in the county of Cook and State 5 of Illinois, have invented certain new and useful Improvements in Lamp Holders and Adjusters, of which the following is a specification.

One of the objects of my invention is to 10 provide a lamp-socket holding means whereby to adjust the position of an incandescent lamp axially and universally in angularly disposed positions.

Another object of my invention is to provide 15 a lamp holding device having a reflector-attaching part whereby to attach and hold the reflector in association therewith and whereby the reflector may be bodily adjusted in a vertical plane with the lamp, 20 providing other means for adjusting the lamp axially of the reflector and laterally thereof to locate the lamp in the true focal plane of or most advantageous position in the reflector.

25 Other and further objects of my invention will become readily apparent, to persons skilled in the art, from a consideration of the following description when taken in conjunction with the drawings, wherein:

30 Figure 1 is an elevation of the lamp holder, adjuster and reflector, showing parts in section.

Fig. 2 is an elevation of the upper part 35 of the device showing the lamp in the axial or horizontal position.

Fig. 3 is a central section of the same portion of the device showing the lamp in an angular position, with respect to the axis.

Fig. 4 is a transverse section taken on 40 line 4—4 of Fig. 1.

Fig. 5 is a similar section taken on line 45 3—5 of Fig. 1.

Fig. 6 is a similar section taken on line 50 6—6 of Fig. 1.

45 In all the views the same reference characters are employed to indicate similar parts.

50 My lamp adjusting device is especially adapted for use with head lights, for locomotives, and other similar light projectors. It may be used in head lights or projectors of steam boats, search lights or the smaller lamps of automobiles employed to illuminate the roadway over which the vehicle is 55 traveling.

The prime object sought is to provide a

stable, practical means whereby to adjust the position of the lamp within its associate reflector, or projector, by conveniently operable means located outside of the projector but preferably within the casing of such structure and so simple and certain in operation that its manipulation may be effected by the use of one hand while the operator is looking into the opposite end of the reflector to observe the adjusted location of the lamp and the effect of the adjustment.

When a lamp is out of true focal position of the parabolic reflector in a head light, especially those used upon locomotives, it 70 requires considerable skill of the engineer or operator, to maintain his upright position on the moving locomotive, while adjusting the position of the lamp unless the lamp adjusting device has such advantageous features as may render it especially adaptable for such purposes.

In the exemplified illustration of my invention 10 represents the base plate upon which the lamp adjuster 11 and the projector 12 are mounted. A threaded stem or pipe 13 is connected to a socket part 14 of the lamp holder and adjuster and is a means by which it is supported upon the base.

The lower portion 15 is screw threaded, 85 and over the threaded end a washer 16 is passed, the upper surface of which normally rests in contact with an adjusting nut 17. A similar nut 18 is located on the other side of the base plate 10 and is held in adjusted 90 position by the check nut 19. By this means the lamp adjuster and the reflector 12 may be vertically adjusted with respect to the base 10. A casing member 20, of which the socket 14 is an integral part, is provided 95 with radially projecting perforated ears 21 and 22. Its front end is provided with an annular flange 23 having a dished face 24 corresponding with the exterior contour of the projector or reflector 12, its outer end 25 is concaved to receive the spherical frustum, universally adjustable collar 26 of the socket holder. The outwardly curved collar 26 is provided with an outwardly extending, preferably integral open cylindrical member 105 27. The interior of the cylindrical part 27 serves as a guide for the screw threaded, cylindrical socket holder 28 and is provided with an annular groove 29. A nut 30 has screw threaded engagement with the threaded portion of the guide 28 and overlies the outer portion of the cylinder 27. The nut 110

is also provided with an annular groove 31, which registers with the groove 29 when the nut is in place. A flat spring 32, substantially semi-circular in form and curved on 5 shorter radii than the cylinder 27, is slotted at its terminal ends, as at 33 and 34, and is held loosely in place by studs or pins 35 that pass through the respective slots and which are secured to the cylindrical portion 27. 10 The spring 32, in its normal, radial position is partly in the groove 29 and partly in the groove 31, serving as a gib, so that so long as the spring is in this position, in the two grooves, the nut 30 has no axial movement 15 on the cylinder 27. The center of the spring is provided with a slight projection 36 which may be produced by indenting the inner surface thereof, which enters perforations 37 made through the walls of the nut at frequent intervals. Now it will be manifest 20 that when the nut 30 is rotated to the right, for example, the socket-holder and guide 28 will be moved outwardly by the threaded engagement of the nut 30 with the guide 28 25 and as shown in dotted lines in Fig. 1 and when the direction of rotation of the nut is reversed the guides will be moved inwardly. By this means the lamp 38, which is supported in a lamp socket 39 may thus be adjusted 30 to any axial position within the capability of the adjusting device. When the nut has been rotated to the proper extent the projection 36 will enter the inner edge of one of the perforations 37 and produce friction 35 tending to prevent the nut from being rotated. To remove the nut from the cylinder 27 it is only necessary to place a small instrument through one of the perforations 37 and press down, toward the axis, upon the 40 apex of the spring 32, preferably in the region of the projection 36, thereby pressing the spring wholly into the groove 29, which will permit the nut and the socket guide 28 to be removed from the casing. The nut 45 may now be unscrewed from the guide 28 and the latter may be taken out from either end of the casing. The guide 28 is provided with a rear perforate wall 28' through which a headed bushing 40 may pass and which is 50 screw threaded into the terminal threaded end 42 of the socket. The flange of the bushing 40 engages the wall 28' to hold the socket in place. A cushion 43, such as a strip of chamois, leather, or the like, may surround 55 the body part of the lamp socket 39 to take the shock due to impact that may be produced by the rapidly moving train, or from other causes which would otherwise affect the socket or lamp, connected thereto. The 60 socket 39 is preferably provided with a flange 41 which may engage the inner end 43 of the guide 28. When the bushing 40 is screwed up it will hold the socket and guide in true axial positions. Wires 44 and 45 65 convey the current to the lamp through the socket. A locking member 46 of the two-part casing 20 for securing the spherical frustum 26 in connection with the part 25 of the casing, in adjusted position, consists of a ring having radially projecting ears 47 and 48 for cooperation with the ears 21 and 22 of the part 20. Screws 49 and 50 pass through clearance holes in ears 47 and 48 and are threaded into the ears 21 and 22. The member is provided on its diametrically opposite side with a projection 51, which is perforated, as at 52, for the relatively fixed threaded stud 53 that projects from the socket 14. A thumb nut 54 is threaded on to the stud 53 and bears against 80 the perforate end of the projection 51, which, together with the screws 49 and 50, serve to frictionally hold the spherical member 26 in the fixed position in which it has been adjusted between the casing members 20 and 85 46. The inner surface of the ring 46 is provided with an annular groove 55, within which is contained friction members consisting of a spring wire 56, which is bent into a more or less rectangular form, having parts 57 yieldingly resting upon the outside surface of the spherical member 26. The object of this spring member is to exert 90 a slight, temporary frictional resistance to prevent movement of the spherical member 26, so that the operator may remove his hand from the nut 30, after he has adjusted the lamp to the proper angular position, and tighten the thumb screw 54 to hold the casing members in contact with the universally 95 adjustable member 26 to positively maintain it in the position in which it has been previously adjusted. Without the spring 56, or some substantial equivalent, the parts would not remain in adjusted position after the 100 operator's hand had become disengaged from the rear projecting portion of the device, such as the nut 30, preliminarily to tightening the nut 54 on the stud 53, to positively hold the parts in the positions in 105 which he had placed them. It is of course manifest that other means than the contorted wire ring 56 may be employed for this purpose, but I have found this to be a very 110 convenient and cheaply produced expedient 115 to accomplish the desired result. A bushing 60, provided with a flange 61, is a means for holding the lamp adjusting device in association with the reflector, or projector 12. The cylindrical portion of the 120 bushing passes through a perforation made through the projector and into the front end of the casing member 20, with the flange 61 of the bushing overlying the edge of the opening in the projector. The bushing 60 is held in place by means of a spring 62 which lies in an annular groove 63, which is provided with terminals that are bent into returned ends, as at 64 and 65. The 125 extreme ends 66 and 67, respectively, are 130

- bent into substantially radial planes. The ends 66 and 67 project through slots 68 that are made into the cylindrical walls of the bushing member 60. The terminal ends 64 and 65 are also bent axially to some extent so as to hold the bushing 60 firmly, but yieldingly in its position with its outer surface resting neatly against the concaved surface of the casing member 20. When it is desired to separate the lamp holding device from the projector it is only necessary to push the terminal ends, 64 and 65, toward the projector and then radially so as to withdraw the radial ends 67-67 out of the respective slots in the bushing, thereby permitting the bushing to slide out of the opening in the front end of the member 20, separating the lamp holding device from the projector.
- 20 Before this is done, of course, the clamping or locking member 46 has been removed, and the socket and the guide 26 and 28 have been also removed from the interior of the casing member 20.
- 25 While I have herein shown a single embodiment of my invention, for the purpose of clear disclosure, it is manifest, to persons skilled in the art that many changes may be made in the arrangement, configuration and disposition of the parts within the scope of the appended claims.

Having described my invention, what I claim is:—

1. A lamp holder and adjuster comprising a two-part casing; an angularly adjustable collar member having a spherical frustum part, between said casing members and a cylindrical part projecting theretrom; an axially movable socket-holding member, within said angularly adjustable collar member; a threaded nut on said cylindrical part to axially move said socket and holder, and means to clamp the casing members in contact with said frustum to hold the socket in adjusted angular position.
2. A lamp holder and adjuster comprising

a two-part casing; an angularly adjustable member, having a spherical frustum part between said casing members and a cylindrical part projecting therefrom; a yielding friction-producing member, interposed between said frustum and casing, to temporarily hold the former in place; an axially movable socket-holding member in said adjustable member; a threaded nut on said cylindrical part to axially move said socket and holder; means to prevent axial movement of the nut; and means to clamp the casing members in contact with said frustum to positively hold the socket in adjusted angular position.

3. A lamp holder and projector comprising a two-part casing divided in a plane transverse to its axis; an angularly adjustable member comprising a spherical frustum contained between said members, and a projecting cylinder; a rotatable nut, axially fixed on said cylinder; an axially movable socket-guard provided with a threaded cylindrical part engaged by said nut; a friction-check to yieldingly hold the nut against rotation and means to clamp said casing members into contact with said frustum to hold the latter in adjusted position.

4. A lamp holder and adjuster comprising a two-part casing; a universally-adjustable socket-holder therein; means to move the socket and holder axially of the casing; means to tighten the two part casing on the holder to retain it in its adjusted angular position; a bushing in the inner end of said casing having an annular, radially extending means to engage a reflector and yielding means in said casing to hold the bushing in place.

In testimony whereof I hereunto set my hand in the presence of two subscribing witnesses.

HENRY E. PROCUNIER.
